GAME APPARATUS

Marvin Gail Pool, Valparaiso, Ind.

Application May 25, 1931. Serial No. 539,937

9 Claims. (Cl. 273—144)

This invention relates to a game apparatus, and has for its object to provide, in a manner as hereinafter set forth, an apparatus of the class referred to having as elements thereof player pieces for controlling its operation and with the apparatus so constructed and arranged to provide for the playing of an amusing game of aggregated values.

A further object of the invention is to provide, in a manner as hereinafter set forth, a game apparatus including a series of normally concealed, differently designating values, points or score indicators capable of being independently released, for vision thereof on each play to indicate the value of the latter made by a player during the playing of the game.

Further objects of the invention are to provide, in a manner as hereinafter set forth, a player piece controlled game apparatus which is comparatively simple in its construction and arrangement, strong, durable, compact, amusing when used, readily assembled and comparatively inexpensive to manufacture.

With the foregoing and other objects in view, the invention consists of the novel construction, combination and arrangement of parts as herein-after more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of a game apparatus in accordance with this invention.

Figure 2 is a side elevation thereof.

Figure 3 is a rear elevation.

Figure 4 is a section on line 4—4 Figure 3.

Figure 5 is a section on line 5—5 Figure 3.

Figure 6 is a section on line 6—6 Figure 1 upon an enlarged scale.

Figure 7 is a section on line 7—7 Figure 6.

Figure 8 is a section on line 8—8 Figure 6.

Figure 9 is an elevation of the form of value, point or score indicators employed.

Figure 10 is a vertical sectional view of the apparatus.

Figure 11 is a section on line 11—11 Figure 6.

Figure 12 is a fragmentary view in section illustrating the chute for the player pieces.

Figure 13 is a section on line 13—13 Figure 6.

Figure 14 is a view of the form of player piece employed.

The apparatus includes a series of player pieces of circular disc like form and a series of normally concealed value, point or score indicators. The player pieces will be hereinafter referred to as checks. The value, point or score indicators will be hereinafter referred to as indicators. Each indicator is of globular form and provided with a number to indicate the value, point or score made by a player on a play and such value, point or score is obtained when the indicator is released for vision thereof. Each indicator is of a different value. The player pieces control the release of the indicators.

The game played is termed a game of aggregated values. Each player will be allotted a like number of checks, by way of example, five, and preferably the game will be played by two players. The player inserts a check in the apparatus and which when inserted permits of the operation by the player of an indicator release mechanism causing the value of an indicator being viewed and the value is then scored by the player. The other player inserts one of his checks in the apparatus, operates the indicator release mechanism causing the value of an indicator being viewed and the value thereof is then scored. After the last check has been played by each player, the values scored by each player are aggregated and the player having the greater value total is the victor.

The form of check or player piece employed is shown by Figure 14 and it consists of a circular disc 1 of the desired thickness and diameter.

The form of value, point or score indicator employed is shown in Figure 9 and it consists of a globular body or ball 2 provided with a plurality of suitably arranged value indicating means, as shown in the form of spaced, like numbers and further to enable the value of the indicator to be readily seen by a player when the indicator is exposed. Any desired number of indicators may be employed and they are normally concealed from a player and successively released for exposure in a manner as hereinafter referred to.

The apparatus includes a housing formed of a base 4, a front wall consisting of a fixed upper and a fixed lower section 5, 6 respectively, a pair of side walls 7, 8, a rear wall formed of a stationary upper and a removable lower section 9, 10 respectively and a top 11. The section 6 inclines rearwardly from the upper end of section 5 of the front wall. The sections 5, 6 have inwardly extending apertured ears 12 positioned against the inner faces of the side walls 7, 8. Holdfast devices 13 extend through the side walls and the ears 12

for detachably connecting the sections 5, 6 in position. The rear wall section 9 is slidably mounted in grooves 14 formed in the inner faces of the side walls. The section 9 has laterally extending tongues 9' which extend into the grooves 14. The side walls 7, 8 are mortised in the base 4 as at 15. The top 11 is formed with depending apertured ears 16 positioned against the inner faces of the side walls 7, 8 and holdfast devices 18' coact with the ears 16 for detachably securing the top 11 in position. The top 11 when mounted in position abuts the top edge of the section 6 of the front wall.

The section 5 of the front wall near its top and at one side thereof is formed with a slot 17 having a beveled lower wall, a circulating opening 18 below the slot 17 and a rectangular slot 19 below the opening 18. Formed integral with the outer face of the section 5 and bordering the ends of the slots 17 and 19 is a pair of spaced, opposed triangular shaped side wall forming members 21 connected together at their outer ends by a front wall forming member 22. The members 21 have grooves 23 in their inner faces near the top thereof and inwardly extending flanges 24 at the bottom thereof. The member 22 is inwardly flanged at its top and bottom as at 25, 26 respectively. Mounted in the grooves 23 of the members 21 and abutting the member 22 below its top flange 25 is an upwardly inclined transparent member or sight glass 27 which has its upper end extended through slot 17 and seated on the beveled lower wall of the latter. A retaining member 28 is mounted in slot 17 for the upper end of glass 27. Seated on flange 26, pivotally connected at its forward end, as at 29 to members 21, extending rearwardly through slot 19 at a downward inclination is a shiftable retaining lever 30 for releasing an exposed indicator from exposed position. The members 21, 22, the lever 30, a part of section 5 and the glass 27 provides a receiving compartment, chamber or receptacle 31 for exposing a released indicator to permit of the value of such indicator being ascertained. The glass 27 forms the top wall of the exposure compartment 31 for the indicator. The lever 30 forms the bottom of the compartment and normally retains the indicator therein so that its value can be readily determined through the glass 27. The lever is shifted in a manner to be hereinafter referred to to provide for the discharge by gravity of the exposed indicator from compartment 31. The opening 18 is an entrance for compartment 31 and the slot 19 provides the outlet thereof. The lever 30 normally functions to prevent the discharge of the indicator and when in normal position is raised in compartment to contract the slot 19. When the lever 30 is moved from normal position it is lowered a distance to permit the indicator discharging rearwardly through slot 19.

The section 5 in proximity to its top and other side thereof is formed with a check entrance slot 32 and directly below such slot 32 with a guide flange 33 to facilitate the entrance of the checks into the slot.

Positioned against, as well as being fixedly secured to the inner face of wall 7 is a check chute which registers at its upper end with slot 32 and extends at a downward inclination from the latter. The chute includes a top plate 34 and a bottom plate 35, the latter being formed with a lengthwise extending groove 36 from end to end thereof. The plate 34 is mounted upon and secured to plate 35 by holdfast devices 37 to pro-

vide in connection with the groove 36 a check passage. The bottom wall of groove 36 in proximity to its lower end is formed with a recess 38 having beveled walls. The top plate 34 has its lower portion provided with a rectangular cut-out 39 which extends lengthwise thereof and which constitutes a clearance for a purpose to be hereinafter referred to. The lower portion of the check passage is of a size to frictionally retain the check 1, that is to say the thickness of the check 1 relative to the area of the lower portion of the check passage is such that it provides for the top and bottom walls of the latter to arrest the travel of the check and to retain it in a position to extend slightly over the lower portion of recess 38 for a purpose to be presently referred to. The plate 35 carries a depending reinforced supporting web 40 which is fixedly secured by the holdfast devices 31 to the wall 7. The manner in which the check 1 is discharged from the check passage will be hereinafter referred to.

The side wall 7 is formed with an opening 42 which is closed by a transparent member or sight glass 43.

Extending into the side wall 7 and abutting the sight glass 43 is a casting comprising a pair of side walls 44, 44', a rear wall 45 inclining from its top to its bottom in a direction towards the wall 7 and a pair of apertured ears 46 through which extend holdfast devices 47 for securing the casting to the wall 7. Positioned within the lower portion of the casting and pivotally connected therewith, as at 48 is a pivoted closure 49 which functions to normally close the bottom portion of the casting. The pivoted closure 48 has a rearwardly directed arm 50 formed with a bifurcated rear end 51. The casting, in connection with sight glass 43 and pivoted closure 49 provides an open top and transparent front check receiving receptacle having a dumping bottom. Positioned in the bifurcated rear end 51 of the arm 50 is a pivot 52 for the lower end of a shifting arm 53 for the closure 49. The closure 49 is shifted to open position against the action of a controlling spring 54 therefor. The spring has its upper end connected to the top of the wall 45 and its lower end to the pivot 52. The means for shifting the arm 53 will be presently referred to. The receptacle is positioned in a manner whereby the side wall 44 will be arranged directly below the lower end of the check chute. The check 1 is kicked from the check chute into the receiving receptacle to enable one to see through the medium of the glass 43 whether the check has passed from the chute or not.

Arranged within the upper portion of the housing and mounted on supports 55 secured to the inner face of the walls 7, 8 is a hopper 56, provided with an eccentrically disposed opening 57 and a depending collar 58 forming a continuation of the wall of the opening 57. The indicators are normally stored within the hopper 56 and are successively released therefrom. The indicators are normally concealed.

Secured to the wall 8 and extending inwardly therefrom is a horizontally disposed casting including an angle shaped part formed with a horizontal arm 59 and a vertical arm 60. The arm 59 has its upper face provided with a boss 61 and said arm is also formed with an opening 62 which communicates with an indicator passage 63 provided by a trough like extension 64 which is integral with and projects from the arm 59. The bottom of the passage 63 at its outer end is formed with a discharge opening 65. The

arm 59 is furthermore formed with a vertically disposed stub shaft 66 which extends above the boss 61. The arm 60 is fixedly secured to the wall 8 by the holdfast devices 67. The arm 59 extends to a position below and spaced from the collar 58.

Mounted on the boss 61 is a vertically disposed oscillatory element 68 for successively releasing the indicators 1 from the hopper 56. The element 68 includes an annular body part 69 which gradually increases in height from one side to the opposite side thereof and is formed with an annular peripheral shoulder 70. The body part 69 partially extends up into the collar 58 and the latter has its lower edge seated against shoulder 70. Formed integral with and disposed centrally with respect to the top of body part 69 is a vertically disposed extension 71 of circular cross section having a rounded top 72. The diameter of the extension 71 is materially less than that of body part 69. The upper face of body part 69 is positioned below and spaced from the opening 57 and is formed with a groove 73 having a high part and a low part and the remaining portion thereof inclining downwardly from the high part to the low part. The body part 69 is also provided with a release opening 74 for the indicators 1 and such opening 74 communicates with the groove 73 through the bottom of the latter. The bottom of groove 73 inclines downwardly towards opening 74. The extension 71 has a centrally arranged depending portion 75 which extends to the boss 61 and is formed with a socket 76 into which extends the stub shaft 66. The body part 69 and portion 75 shift upon the boss 61. The body part 69 is formed with a radially disposed arm 77 having a vertical opening 78. The element 68 is spring controlled and the controlling spring therefor will be presently referred to. The opening 62 formed in the arm 59 is partly closed by the body part 69 of the element 68 when the latter is in normal position. When the element 68 is shifted in one direction the opening 74 is adapted to register with the opening 62 whereby an indicator will pass through the registering openings into the passage 63 and be discharged from such passage 63 through the opening 75 into a transferring element to be presently referred to.

Journalized in the wall 8 and extending through and projecting from the wall 7 of the housing is a rock shaft 79 having fixed thereto and bodily moving therewith an indicator transferring element referred to generally at 80. The element 80 consists of a circular body portion 81 provided with a radially disposed socket 82 opening at the edge of the latter and adapted to register with opening 65 for the purpose of receiving the released indicator from the passage 63. The transferring element 80 is arranged over an indicator conducting element 83 and the latter is adapted to receive the indicator from the element 80. The element 83 is inclined downwardly in a direction towards wall 8, is formed of trough like body part 84 and integral with the inner face of section 5 of the front of the housing. The lower end of body part 84 is arranged to partly surround opening 18 and communicates with the latter. The indicator passes down element 83 and is discharged therefrom through opening 18.

Fixed to the shaft 79 in proximity to the side wall 8 is a rearwardly extending arm 85 having its rear end attached as at 86 to a rearwardly extending and upwardly inclined controlling

spring 87, and the latter having its upper end fixed, as at 88 to the wall 8. The spring 87 is common to the shaft 79 and element 68, as well as certain of the other elements of the apparatus which are carried by the shaft 79. Fixed to the shaft 79, in proximity to the arm 85 is a crank member 89 of yoke shaped form and in which is pivotally connected, as at 90, an angle shaped locking member 90 formed of a leg 91 and a foot 92. The foot 92 in proximity to one end thereof is provided with a shouldered heel 93 and at its other end with a depending toe 94. Attached to the leg 91 and coupled with the plate 34 is a controlling spring 95 for the member 90. The foot 92 of member 90 acts to shift or kick check 1 from the lower portion of the check chute. When the check is not in the chute the heel 93 engages in the recess 38 and locks the mechanism from action. The downward movement of the member 90 is arrested when check 1 is in the position shown in Figure 12. When the downward movement of member 90 is arrested by check 1, the heel 93 engages the upper edge portion and the toe 94 the lower edge portion of check 1. When the member 90 moves to normal position, which is as shown in Figure 11, the heel 93 kicks or shifts check 1 out of the check chute into the check receiving receptacle. The cutout 39 provides a clearance for the foot 92 when the latter moves towards the check chute. When check 1 is not in the check passage the heel 93 will enter recess 38 and in connection with the walls of the latter lock the apparatus. If check 1 is in the lower portion of the check passage, then the downward movement of member 90 is arrested and the heel cannot enter recess 38 and the apparatus will be set for the purpose of releasing an indicator from the hopper on the next play.

The means or mechanism for operating the arm 53 for the purpose of rocking the closure 49 to discharge the check from the collecting receptacle comprises a link 96 which is pivotally connected at one end, as at 97 to a yoke 98 carried on the inner face of the section 5 of the front wall. The rear end of link 96 is forked as at 99 and pivotally connected as at 100 to the upper end of arm 53. Pivotally connected as at 101 to the link 96 is the forked lower end 102 of a shifting member 103 for the link 96. The member 103 is shouldered, as at 104 and the shoulder 104 is engaged by the base 105 of a yoke shaped crank member 106 clamped to the shaft 79 and between which the upper end of the member 103 extends. The member 103 is spring controlled and its controlling spring is indicated at 107. The spring 107 has one end attached to the section 5 of the front and its other end attached to the member 103 in proximity to the shoulder 104 thereof. When the shaft 79 is shifted in a clockwise direction, the base of the crank 106 shifts the upper portion of member 103 downwardly which in turn elevates the link 96, the latter carrying the arm 53 therewith, the arm 53 will open the bottom of the check receptacle and provide for the discharge of the check therefrom. When the shaft 79 is moving in a clockwise direction the locking member 90 is moved downwardly simultaneously with the shifting of the upper portion of the member 103 downwardly.

Depending from the outer end of arm 77 is a yoke 108 formed with an arm 109 which extends up through the opening 78 and is connected with arm 77 by a pin 110. Pivotally connected to the yoke 108 is the rear end of a pull rod 111. Fixed

to the shaft 79 is an upstanding crank arm 112 having a forked upper end 113 to which the forward end of pull rod 111 is pivotally connected as at 114.

5 The normal position of element 68 is as shown in Figure 6 and when shaft 79 is moved in a clockwise direction the openings 62 and 74 will register to permit of the release of an indicator from the hopper. When shaft 79 is moved by the action of its controlling spring in an anti-clockwise direction the element 68 will assume the position shown in Figure 6 that is if there is a check 1 in the lower portion of the check passage. If there is no check 1 in the lower portion of the check passage, then the locking member will engage in the recess 38 and prevent the return of the mechanism to normal position, under such conditions locking the machine from further action and prevent a continuance of the game.

26 After the indicator has passed into its receiving chamber or compartment, and another play is made and such play being the insertion of the check and the shifting of the rock shaft in a clockwise direction and on such operation 25 of the shaft, the indicator will be discharged from its receiving chamber or compartment due to the shifting of the lever 30 from the position shown in Figure 7 to permit of the indicator passing into the housing through the outlet 19. The lever 30 is operated by a link 115 pivoted at its lower 30 end to the inner end of lever 30 and at its upper end to a crank arm 116 carried by the shaft 79.

Connected to that end of the shaft 79 which projects from the side wall 7 of the housing is a 35 lever handle 117 which is disposed at an outward inclination from its lower to its upper end with respect to the housing. Secured to the wall 7 is a stop 118 for arresting the inward shift of the handle 117, the latter being formed with a lug 40 119 which is adapted to abut the stop 118.

The section 10 of the back wall carries a key 45 operated lock 118' and the locking bolt 119' of the latter is adapted to engage in a socket 120 formed in the rear of the base 4 to lock section 10 in closed position.

Secured upon the upper face of base 4 at the rear thereof is a pair of spaced abutments 121 to arrest the inward shift of the lower portion of section 10. The top of section 10 has a pair of 50 upstanding, spaced offset flanges 122 and the bottom of section 9 has a depending offset flange 123. The section 9 seats on the top edge of section 10, and when in such positions, the flanges 122 and 123 abut respectively the inner faces of 55 sections 9 and 10 to prevent the upper portion of the latter from swinging outwardly or inwardly when section 10 is locked. The detachable section 10 enables access to be had to the interior of the housing.

60 The exposed indicators and the inserted checks are discharged into the lower portion of the housing.

What I claim is:—

1. In a game apparatus, a series of normally concealed releasable value indicators, a compartment for exposing a released indicator to ascertain the value thereof and including an intake opening and a discharge slot, means for successively releasing the concealed indicators and for conducting them to said compartment for exposure, a locking member for said means, means for controlling the locking function of said member with respect to said releasing means, a shiftable discharge control means for the exposed indicators extending into said compartment

through said discharge slot and pivoted at one end within the compartment and arresting the discharge of an exposed indicator from said compartment until the release of a concealed indicator, and an actuating shaft for and common to 80 said releasing and discharge control means and said member.

2. In a game apparatus, a container for storing and normally concealing a series of releasable value indicators, a compartment for exposing a released indicator to ascertain the value of the latter, means for successively releasing said indicators from said container and for conducting them to said compartment for exposure, said compartment having an intake opening and a 85 discharge slot, and actuatable means extending through said slot to normally contact the latter to arrest discharge of an exposed indicator and actuatable to provide for the discharge of an exposed indicator through said discharge slot on 90 the release of a concealed indicator.

3. In a game apparatus, a series of normally concealed and releasable value indicators for exposure, a compartment for exposing successively released indicators, means for successively releasing said indicators and conducting them to said compartment for exposure, successively played player pieces for controlling the operation of said means to provide for the discharge of an exposed indicator from said compartment on the 100 release of a concealed indicator, a receptacle for exposing said successively played player pieces, and means to provide for the discharge of an exposed player piece simultaneously with the discharge of an exposed indicator. 105

4. In a game apparatus of that type including player pieces and normally concealed releasable value indicators, a container for said indicators, a compartment for exposing a released indicator to ascertain the value of the latter, a receptacle 110 for exposing a played player piece, means for successively releasing the indicators from said container and for conducting them to said compartment for exposure, means to provide for the discharge of an exposed indicator from said compartment on the release of a concealed indicator, and means extending into and pivoted at one end within said compartment to provide for the discharge of an exposed player piece from said receptacle simultaneously with the discharge of an 115 exposed indicator.

5. A game apparatus comprising an exposure compartment for a value indicator, a container for concealing value indicators, a vertically disposed oscillatory element extending into said container for successively releasing the value indicators from the latter, a horizontal support for and including a vertically disposed pivot for said element, a value indicator conducting means discharging into said compartment, an oscillatory value indicator transferring element discharging into said conducting means and operating on an axis at right angles to the axis of said element, means for receiving a released value indicator from said oscillatory element and for discharging same into said transferring element, means to provide for the discharge of an exposed indicator from said compartment on the release of a concealed indicator from said container, independent operating mechanism for said oscillatory releasing element and discharge means, and a spring controlled rock shaft carrying said transferring element and mechanisms for operating them in opposite directions. 120

6. In a game apparatus, a housing having its 125

front provided with a compartment for exposing a value indicator, a hopper for holding and concealing value indicators, said hopper supported within the housing, a vertically disposed, grooved, 5 apertured oscillatory value indicator releasing device extending into said hopper for successively releasing the indicators therefrom and operating upon a vertical axis, means for receiving the successively released indicators and for 10 conducting them to said compartment for exposure to ascertain their values, said means including an oscillatory element operating on an axis at right angles to the axis of said device provided with a socket to receive an indicator, 15 and means to provide for the discharge of an exposed indicator on the release of a concealed indicator. 19

7. In a game apparatus, a housing having its front provided with a compartment for exposing a value indicator, a hopper for holding and concealing value indicators, said hopper supported within the housing, a vertically disposed, grooved, apertured oscillatory value indicator releasing device extending into said hopper for successively releasing the indicators therefrom and operating upon a vertical axis, means for receiving the successively released indicators and for conducting them to said compartment for exposure to ascertain their values, said means including an oscillatory element operating on an axis at right angles to the axis of said device provided with a socket to receive an indicator, said housing having its front provided with a slot for the successive playing of player pieces, a receptacle for exposing successively the played player pieces, and means for simultaneously discharging the exposed indicator and player piece from said compartment and receptacle on the release of a concealed indicator. 25

8. In a game apparatus, a housing having its front provided with a compartment for exposing a value indicator, a hopper for holding and concealing value indicators, said hopper supported 30

within the housing, an oscillatory value indicator releasing device extending into said hopper for successively releasing the indicators therefrom and including a vertically disposed base having a vertical aperture and an upstanding extension 80 integral with the base, the upper face of the base having a groove inclining downwardly towards the aperture, said element being operable upon its vertical axis, means for receiving the successively released indicators and for conducting 85 them to said compartment for exposure to ascertain their values, said means including an oscillatory element provided with a socket to receive an indicator, and means to provide for the discharge of an exposed indicator on the release of 90 a concealed indicator. 91

9. In a game apparatus, a housing having its front provided with a compartment for exposing a value indicator, a hopper for holding and concealing value indicators, said hopper supported 95 within the housing, an oscillatory value indicator releasing device extending into said hopper for successively releasing the indicators therefrom and including a vertically disposed base having a vertical aperture and an upstanding 100 extension integral with the base, the upper face of the base having a groove inclining downwardly towards the aperture, said element being operable upon its vertical axis, means for receiving the successively released indicators and for conducting 105 them to said compartment for exposure to ascertain their values, said means including an oscillatory element provided with a socket to receive an indicator, said housing having its front provided with a slot for the successive playing 110 of player pieces, a receptacle for exposing successively the played player pieces, and means for simultaneously discharging the exposed indicator and player piece from said compartment and receptacle on the release of a concealed indicator. 115
